UNITED STATES PATENT OFFICE

166,475

AIRSHIP

Raymond F. Lewis, Vancouver, British Columbia,
Canada

Application March 9, 1950, Serial No. 8,410

Term of patent 3½ years

(CL. D71—1)

To all whom it may concern:

Be it known that I, Raymond F. Lewis, a citizen of the Dominion of Canada, residing at Vancouver, in the Province of British Columbia, Canada, have invented a new, original, and ornamental Design for an Airship, of which the following is a specification, reference being had to the accompanying drawing, forming part thereof.

Fig. 1 is a side elevational view of an airship showing my new design;

Fig. 2 is a front elevational view of the same; and

Fig. 3 is a top plan view of the same.

The characteristic features of my design reside in the parts shown by means of full lines in the drawing.

I claim:

The ornamental design for an airship, as shown and described.

RAYMOND F. LEWIS.
